US0D1078462S

(12) **United States Design Patent** (10) Patent No.: **US D1,078,462 S**
(45) Date of Patent: ** Jun. 10, 2025

(54) **LOCKING CONNECTOR FOR SHEET PILES**(71) Applicant: **Sergey Aleksandrovich Voloskov**, g.
Omutninsk (RU)(72) Inventors: **Aleksandr Dmitrievich Voloskov**,
obl.Kirovskaya (RU); **Sergey Aleksandrovich Voloskov**,
obl.Kirovskaya (RU)(**) Term: **15 Years**(21) Appl. No.: **35/518,474**(22) Filed: **Sep. 27, 2022**(80) **Hague Agreement Data**Int. Filing Date: **Sep. 27, 2022**Int. Reg. No.: **DM/229834**Int. Reg. Date: **Sep. 27, 2022**Int. Reg. Pub. Date: **Sep. 29, 2023**(51) LOC (15) Cl. **08-08**

(52) U.S. Cl.

(Continued)

Primary Examiner — Sheryl Lane*Assistant Examiner* — Ieisha N Price(74) *Attorney, Agent, or Firm* — Brett A. Schenck(57) **CLAIM**

The ornamental design for a locking connector for sheet piles as shown and described.

DESCRIPTION

2. Locking connector for sheet piles

2.1: Perspective

2.2: Left

2.3: Top

2.4: Front

2.5: Back

The Locking connector for sheet piles is used to connect wall-forming elements.

1 Claim, 5 Drawing Sheets# US D1,078,462 S
